Joseph Phelps, Stamford, Conn., assignor to
Remington Rand Inc., New York, N. Y., a cor-
poration of Delaware

Application March 24, 1933, Serial No. 662,484

45 Claims. (Cl. 120—29)

My invention relates to copyholders and the objects of the invention, generally stated, are as follows:

To provide a highly effective and easily manipulated copyholder for indicating the lines successively, line at-a-time as they are being copied.

To provide simple and efficient means for intermittently, successively and noiselessly feeding the copy line at-a-time and in which the extent of each line space, intermittent feed may be varied at will.

To provide highly effective means that are simple and reliable in their operation for readily returning the work sheet carrier to its initial position with but little or no noise from any position to which the work sheet carrier may have been intermittently fed.

To provide improved means whereby the copyholding member may be readily expanded to its fullest height during the feed of the copy, or may be readily collapsed to the first line indicating position.

To provide a construction of the character hereinbefore set forth with means whereby the copyholder may be further collapsed from its first writing line position to a position of non-use where it may be moved into a drop cabinet of a typewriting machine with said machine, and without interfering with the movement of the machine into and out of the cabinet.

To the above and other ends which will hereinafter appear, my invention consists in the features of construction, arrangements of parts and combinations of devices set forth in the following description and particularly pointed out in the appended claims.

In the accompanying drawings wherein like characters indicate corresponding parts in the different views—

Fig. 1 is a perspective view of the copyholder with the copy-carrying member shown in the first line indicating position.

Fig. 2 is a side view of the copyholder shown in the rear of the typewriting machine; the dotted lines showing the copyholder in its fully expanded position and the full line showing of the copyholder representing the parts as they appear when the copyholder is fully collapsed.

Fig. 3 is a rear view of the copyholder with the parts disposed as they appear when that copy-carrying member is in its first line indicating position and with the rear cover plate removed.

Fig. 4 is a fragmentary, detail, transverse, sectional view of the copyholder taken on the line

4—4 of Fig. 3 and looking in the direction of the arrows at said line.

Fig. 5 is a fragmentary, vertical sectional view taken centrally through the telescoping guide members.

Fig. 6 is a side view of the copyholder with parts omitted and parts in section.

Fig. 7 is a fragmentary detail, front view, with parts omitted, of the actuating drum and some of the associated parts; the view showing the 10 parts as they appear when conditioned to effect a feeding operation of the drum.

Fig. 8 is a fragmentary like view of the same showing the parts as they appear when the drum is released from the control of its actuating 15 mechanism.

Fig. 9 is a side view with parts in section of a portion of the means for controlling the drum.

Fig. 10 is an enlarged detail transverse sectional view of a part of the same taken on the 20 line 10—10 of Fig. 9 and looking in the direction of the arrows at said line.

Figs. 11 and 12 are detail perspective views of the detents for parts of the structure to be hereinafter described.

Generally stated, the present construction involves a work sheet carrying member that may be intermittently and noiselessly fed to an expanded position, represented in dotted lines in Fig. 2, and may at will be readily and noiselessly 30 returned to the first line indicating position, represented in Figs 1 and 3. When it is desired to fully collapse the copyholder to the full line position shown in Fig. 2, and as represented in Fig. 5, to house the copyholder with the typewriting 35 machine in a drop cabinet, this may be readily and noiselessly effected, as will hereinafter appear.

In the accompanying drawings I have shown an L-shaped base comprising two wooden members 40 1 and 2 which are preferably detachably united or hinged together by suitable means to enable the copyholder to be compactly packed when desired. In the present instance screws 3 firmly connect the members 1 and 2 together. The base member 1 constitutes a support for the copyholder proper and the member 2 constitutes a support for the manually controlled handle and certain of the connections controlled thereby. 45 However, the so-called base members 1 and 2 may be dispensed with and the copyholder secured directly to the top of a desk or table on which it is to be supported. For the purpose of the present case the base members 1 and 2 may 50 55

be regarded as the equivalent of a desk or table to which the copyholder may be secured.

As best shown in Figs. 3 and 5 a fixed guide tube or sleeve 5 is fitted at its lower end in an opening in a metal plate or block 6^a secured by screws 6^b to a metal base plate 6 which in turn is fastened by screws 7 to the wooden base member 1, or to the top of the disk or table. Received and telescoping in the guide tube 5 is a tubular member 8 received at the upper and lower end portions thereof with a snug fit in the guide tube 5 which nevertheless permits the member 8 to slide freely within the guide member 5. In a like manner an inner telescoping solid rod 9 is received in the tubular member 8 and has a snug fit at the top and bottom thereof within said member 8. Any suitable means may be provided for limiting the upward telescoping movements of the members 8 and 9 relatively to one another and to the supporting tubular member 5. Thus, by referring more particularly to Fig. 5, it will be seen that the member 8 is provided at the lower end thereof with a head 10 that has a circumferential flange that extends beyond the outer diameter of the tube 8 and is adapted to coact with a shoulder 11 near the upper end of the guide tube 5 to limit the upward movement of the member 8. In a like manner the rod 9 is provided with a head 12 that has a circumferential flange that projects beyond the diameter of the member 9 and is adapted to coact with a shoulder 13 near the upper end of the tubular member 8 and thus limit upward movement of the member 9 relatively to the tube guide member 8.

In order to further secure the tubular guide member 5 in place I provide a cross brace 14 (see Fig. 3) which is secured at its ends by screws 15 to upright supporting members 16^a. The members 16^a constitute rearwardly and inwardly turned parts of an upright sheet metal supporting plate 16 that is coextensive with the width of the copyholder and is fixedly secured at the lower end thereof to the metal base plate 6. The upper edge of the plate 16 terminates at about the height of the bar 14, as shown in Fig. 5. The cross brace 14 is fixedly though detachably connected to the fixed sleeve 5 by a screw 17, as shown in Figs. 3 and 5, to firmly hold the sleeve in place.

I preferably provide a rubber disk 18 in the lower end of the tubular guide 5 and which rests upon a closing block 19 in the lower end of said tubular guide. The purpose of this construction is to seal the lower end of the tubular guide so that said guide and the member 8 may operate in the nature of a dash-pot to prevent too rapid a movement of the guide members and the parts connected therewith when they return to collapsed position. In a like manner the inner guide member 9 in a measure coacts with the tubular member 8 to form a dash-pot.

Referring more particularly to Fig. 3 it will be seen that the upper end of the inner rod 9 is connected by a screw 20 to a cross head 21. This cross head carries two depending pins 22 near the outer ends thereof, each provided at its lower end with a head 23. These pins 22 are received and play freely in openings in a bracket plate 24 that is secured to a member of a lazy tongs, designated as a whole by the reference numeral 25. This connection between the headed pins 22 and the lazy tongs provides a lost motion connection between them, so as to afford a limited extent of independent movement between such parts when the copyholding member

30 is closely approaching and is being moved from its fully collapsed position in a manner and by means which will be hereinafter described. As the lazy tongs are moving to their fully contracted position from that shown in Fig. 3 the rod 9 will be arrested first. The bracket 24 will then move down independently of the arrested pins 22 during the final collapsing movement of the lazy tongs; the heads 23 limiting the final extent of this independent movement. During the upward movement of the copy-sheet carrying member 30, by means to be hereinafter explained, the lazy tongs will be expanded, first carrying the bracket 24 up on the pins 22 until said bracket reaches the cross head 21, as shown in Fig. 3. This will result in lifting the rod 9 and successively expanding the telescoping members 9 and 8 relatively to the fixed member 5. Each of the two lower members of the lazy tongs is connected by a pin and slot connection 26, 27 to the upright supporting plate 16, so as to permit a slight horizontal movement of these lowermost members of the lazy tongs during the expansion and contraction of the lazy tongs.

In a like manner the uppermost members of the lazy tongs are connected by pin and slot connections 28, 29 to a sheet metal member 30 that extends throughout the width of the copyholder and is bent to the rear at the upper end thereof as shown in Figs. 1, 5 and 6. This member 30 constitutes a copyholding member as will hereinafter more clearly appear.

The lazy tongs are further guided by a pin 25^a carried thereby and which moves in an upright slot 25^b in the supporting plate 16 as best shown in Figs. 3 and 4.

From the foregoing description it will be understood that as the lazy tongs are expanded by an elevation of the copy-carrying member 30 the rod 9 will be elevated. On the other hand, when the lazy tongs are contracted during the lowering of the copyholding member 30 the rod 9 will be lowered. It will be understood, moreover, that in these movements of the copyholding member 30 it is guided by the lazy tongs and is constantly maintained in a horizontal position irrespective of the position to which the copyholding member 30 is raised or lowered. The lazy tongs also maintains the copyholding member against a pivotal movement around the telescoping guide members.

In order to further properly guide the copyholding member 30 and prevent it from moving forward or back or sidewise, I have provided a depending sheet metal guide 31 which is fixedly secured at its upper end, as indicated at 32, to the copyholding member 30. The guide member 31 is slotted vertically at 33 to receive a headed pin 34 carried by one of the members of the lazy tongs. This guide in cooperating with the lazy tongs also prevents a side displacement of the copyholding member relatively to the lazy tongs.

From an inspection of Figs. 1, 2 and 3 it will be seen that the copyholding member 30 is provided at the ends thereof with rearwardly extending bracket arms 35. Each bracket arm is pierced to receive one of the longitudinally extending bearing end portions 36 of a bail 37. Each part 36 is surrounded by a coiled spring 38 which is fixed at one end thereof to a collar 39 secured by a set screw 40 to the companion bearing arm 36. The other end of the spring is fixedly secured to the companion bracket 35, as indicated in Fig. 12. As shown in this figure the end of the spring 38 which is connected to the

associated bracket is received through a pierced opening therein and extends upward outside of the bracket where it is provided with a raised portion 41 that coacts with a crank arm portion 42 of the bail and constitutes a detent to hold the bail in its released position. Each spring 38 is shaped to form such a detent so as to maintain the bail in a substantially horizontally disposed released position when the bail is shifted to such position. The cross bar of the bail extends across the copyholder and is provided with a series of rollers 43 which by means of the springs 38 are pressed against the depending portion of the copy carrier 30, or the interposed flexible copy sheet supporting member 44, as will hereinafter more clearly appear.

A second sheet metal clamping member 45 conforming in part to the shape of the work sheet carrying member 30 is secured thereto by screws 46. The lower clamping edge 47 of this plate bears against the upper edge of the flexible sheet or member 44 and with the aid of the screws 46 fixedly connects the upper end of such flexible member and the copyholding member 30. The bail 37 is effective to clamp the upper end of a sheet to be copied against the depending portion of the copyholder 30 or the sheet 44 interposed between said copyholding member and the bail, and thereby cause the copy sheet to be elevated with the copyholding member 30 as the latter is intermittently fed upward, as will hereinafter more clearly appear.

The lower end of the flexible sheet 44, which may be of a textile fabric or other suitable material, is secured to a roller 48 mounted at its ends in bearing brackets 49 carried by the metal base plate 6. This roller is provided with a coiled spring 50 (see Fig. 5) which tends to turn the roller in a clock-wise direction as the parts appear in this view and to take up and wind on the roller the flexible sheet 44 as the work sheet carrying member 30 moves down from an elevated position. The purpose of the flexible sheet 44 is to provide a support against which the copy sheet or sheets may bear to prevent the latter from coming in contact with the lazy tongs or other working parts of the structure when the member 30 is in an elevated position. The force of the spring 50 is exerted on the flexible sheet 44 primarily to maintain it taut at all times, although some of the force of the spring is exerted to return the copyholding member 30 and the parts connected therewith when said holding member 30 is lowered. This latter effect, however, is unnecessary, since the weight of the parts, ordinarily is sufficient to return them to lowered position.

From a consideration of Figs. 1, 2 and 3 it will be seen that each of the upright portions 16a has a bracket 51 secured thereto, at 52, near the upper end thereof. Each bracket is provided with a cylindrical rubber buffer 53 with which the associated bracket 35 coacts to limit the downward movement of the copy-carrying member 30 when the latter moves down to its lowermost position, shown in full lines in Fig. 2. These rubber buffers therefore constitute the means for limiting the downward movement of the copyholding member 30 and the parts carried thereby. This is a fully contracted position of the copyholder to enable it to be conditioned for non-use or to enable it to be received in a drop cabinet with the typewriting machine when the latter is received in such cabinet.

I have provided a line indicating plate 54

which in the present instance is mounted on lazy tongs comprising two members 55 and 56 (see Fig. 1) pivotally united at the centers thereof, as indicated at 57. One end of the member 55 is pivotally connected at 58 to the line indicating plate 54 near one end thereof. The other end of this member 55 is pivoted at 59 to a block 60 mounted for sliding and pivotal movement on the headed pin 61. Said pin projects from an arm 62 fixedly connected to a rock shaft 63 that receives a bearing in the brackets 51 and extends in the rear of the copyholder from side-to-side thereof. A coiled expansion spring 64 surrounds the shaft 63 at one end thereof and tends to exert its force longitudinally on the shaft to move it to the right, or to the left as the parts appear in Fig. 3. Secured to the shaft 63 near the other end thereof is a crank arm 65 provided with two stops 66 which coact with a fixed pin 67 projecting laterally from the outer face of the companion bracket 52. The arm 65 is provided with two openings or recesses 68, one or the other of which is adapted to coact with a rounded projection 69, as shown in Fig. 11. This constitutes a detent 15 to hold the shaft 63 and the parts carried thereby against accidental displacement from either the full line or the dotted line position shown in Fig. 2. In the full line position the parts are positioned for non-use or for storage and with 30 the line indicator overlying the work sheet carrying member 30, whereas in the dotted line position the parts are conditioned for use. The left-hand end of the lazy tong member 56 is pivoted at 70 to a block 71 which in turn is 35 mounted to receive a pivotal movement around a headed pin or screw 72 connected to the left-hand arm 73 which corresponds to the arm 62 that is fixed to the shaft 63.

From the foregoing description it will be understood that the line indicating plate 54 not alone is adapted to move with the shaft 63 from the dotted to the full line position shown in Fig. 2, but that said indicating plate is also free to turn on its pivotal center 61, 72, the parts 45 being sufficiently friction tight to hold the line indicator in any such angular position to which it may be turned on its pivotal center. This enables the line indicator to be adjusted closer to or further from the copy to compensate for 50 various thicknesses of copy, and also to be adjusted out of the path of the bail 37 and the rollers 43 carried thereby, and enables the latter to clear the line indicator when the copy-holding member is lowered to its lowermost position. 55

It also will be understood that the lazy tong mounting provided for the line indicating plate 54 enables it to be moved on its supports 60, 71 to various positions parallel with its pivotal center 61, 72, thereby enabling the line indicator to 60 be moved to and maintained at different elevations. It will be understood that in such movements of the line indicator the right-hand end of the lazy tong section or element 56 will receive a sliding movement relatively to the line 65 indicating plate by reason of the pin and slot connection 74, 75 by which said lazy tong element is connected with the line indicating plate 54.

In order to limit the downward movement of 70 the copy-carrying member 30 and the parts carried thereby to the first line indicating position, I have provided automatically operating devices which I will now describe. Referring more particularly to Figs. 1 and 3 of the drawings 75

- it will be seen that two stops 76 are pivoted on the headed pins 28 which connect the lazy tongs to the copy-carrying member 30. The weight of these parts 76 tends to move them to the position indicated in Fig. 3 where they are adapted to coact with the rubber buffers 53 and limit the descent of the copy-carrying member 30 and the parts carried thereby. When it is desired to fully collapse the copyholder to the position indicated in full lines in Fig. 2 and in Fig. 5, it is merely necessary to swing the member 76 inward towards the center of the copyholder so that the lower ends of said members are out of cooperative relation with the rubber buffers 53.
- 5 The copyholding member 30 may then drop by gravity, aided, if this be found necessary, by the pull of the spring 50 exerted through the sheet 44, to lowermost position. This movement is free from control of the members 76 which at 10 this time coact with the inner sides of the buffers 53 which hold them in ineffective position. As soon, however, as the copyholding member 30 is again elevated to a position where the arresting members 76 are free from contact 15 with the buffers 53, said arresting members will by gravity move to the effective position shown in Fig. 3, where the lower ends of said members are adapted to coact with the buffers and arrest the member 30 in its next downward or return 20 movement. The effect of this arrest of the copyholding member by the arresting devices 76 is to locate the copyholding member and the parts carried thereby in the first writing line position where the line indicator 54, if properly adjusted, 25 will register with the first line of the matter to be copied.
- The means by which the copyholding member 30 is intermittently elevated a line space at a time will now be described.
- 40 A bracket 77 (see Figs. 3 and 6) is secured to the rear side of the depending portion of the copyholding member 30, as indicated at 78. A metal rod 79 is secured at its upper end to said bracket and extends through openings in guide brackets 80 and 81 secured by screws 82 to members of the lazy tongs 25. The lower end of the rod 79 is threaded at 83 for cooperation with a threaded bushing 84. This bushing is received and threaded into the upper end of a flexible controlling or driving member or follower 85 which is in the nature of a closely coiled spring that extends down from and forms a continuation of the rod 79, as indicated in Fig. 3. This flexible member or driving device 45 50 55 60 65 70 75 80 85 90 95 100 105 110 115 120 125 130 135 140 145 150 155 160 165 170 175 180 185 190 195 200 205 210 215 220 225 230 235 240 245 250 255 ing end 113 of the holding pawl and turns it on its pivot 110 to its releasing position, as shown in Fig. 8. In order to limit the extent of releasing movement of the pawl 109 I provide 5 a stop lug 115 that forms part of the bracket 93 and extends into the path of said pawl. The pawl 109, like the pawl 102, is likewise provided with a flexible arm 116 having flexible teeth 117 that bear against the inner side wall of the 10 drum 88. The effect of this frictional engagement between the arm 116 and the drum is to automatically disengage and maintain the holding pawl disengaged from the teeth of the ratchet wheel 94 when the drum is moved in an anti- 15 clockwise direction by the feed pawl 102. As soon, however, as a step-by-step feed movement of the drum is completed and it starts to turn in the opposite direction, then the frictional engagement will cause the pawl 109 to engage 20 the ratchet wheel and prevent a reverse rotation thereof.

The parts are maintained as they appear in Fig. 7 during the line spacing feeding operation of the drum in an anti-clockwise direction. I 25 have, however, provided means for freeing the drum from control of its intermittently operating feeding means when it is desired to lower the copyholding member 30. This is effected by a movement of the link 106 to the left from its 30 normal position as shown in Fig. 8, instead of to the right from its normal position as shown in Fig. 7, when the drum is being fed to elevate the copy-carrying member 30. It will be understood that the movement of the link 106 to the left from its normal position as shown in Fig. 8, instead of to the right from its normal position as shown in Fig. 7, when the drum is being fed to elevate the copy-carrying member 30. It will be understood 35 that the movement of the link 106 to the left from its normal position is effective to positively disengage the holding pawl 109 from the ratchet wheel. This same movement of the link is likewise effective to move the feed pawl 102 out of engagement with the ratchet wheel due to the 40 frictional engagement of the arm 104 with the inner face of the drum. The drum being freed at this time from the control of the pawls 102, 109, is free to turn in a clockwise direction as shown in Fig. 8, thus enabling the copy sheet 45 carrying member 30 and the parts carried thereby to move down to the first line indicating position shown in Figs. 1 and 3 where it is arrested by the stopping devices 76 coaxing with the rubber buffers 73. Should it be desired to still 50 further lower the copy-carrying member 30, this may be done as hereinbefore indicated by moving the stop members 76 inward to disengage them from the buffers 53 when the copy-carrying member 30 is free to move to its lowermost position, shown in Fig. 5 after the pawls 109 and 102 55 are released as explained.

The means by which motion may be transmitted to the link 106, either to effect an intermittent feed of the drum or to free the drum 60 from the control of the actuating devices therefor, will now be described.

As best shown in Figs. 1, 2, 9 and 10 the right-hand end of the link 106 is pivoted to a crank arm 118 which is fixedly secured to a shaft section 119 supported in a U-shaped bearing member or bracket 120 secured to the right-hand upright portion 16^a, as indicated at 121. The forward end of this shaft section forms a tubular bearing 122 that is slotted longitudinally on 65 opposite sides, as indicated at 123. A shaft section 124 carries an enlarged end 125 that is received in the tubular bearing portion of the shaft section 119. Oppositely directed pins 126 carried by the enlarged portion 125 are received in 70 the slots 123 to afford a limited sliding motion of 75

the shaft section 124 relatively to the shaft section 119, but to connect the two shaft sections, nevertheless, to turn together, for purposes which will hereinafter more clearly appear. The shaft section 124 is provided with an enlarged tubular portion 127 tapped to receive pointed set screws 128. A third shaft section 129 is received at one end in the tubular enlargement 127 and is fixedly connected thereto by the screws 128 both to turn and to move longitudinally therewith. The 10 pointed ends of the screws 128 are received in an open ended groove 129^a in the shaft section 129. By these means the shaft 124, 129 may be relatively adjusted to lengthen or shorten the compound shaft to accord with different lengths of 15 typewriting machines with which the copyholder may be associated. The forward end of the shaft section 129 is received in and projects through a bearing opening in a bracket 130 secured by screws 131 to the base member 2. A finger piece 20 132 is provided at the outer end of a crank arm 133 secured to the outer end of the shaft section 129 where it extends beyond the supporting bracket 130. The member 133 is also provided with an arm 134 that carries a screw stop 135 25 held in its adjusted position on said arm by a lock nut 136. The free lower end of the screw stop 135 coacts with a stop face 137 on the bracket 130 to limit the movement transmitted to the shaft 129, 124, 119, in one direction, that is 30 in the direction of its feed movement. It will be understood, therefore, that an adjustment of the screw stop 135 is effective to regulate the extent of line spacing movement transmitted to the compound shaft just described and the feed 35 drum 86 controlled thereby. This affords an adjustment and regulation of the device to set it to accord with the spacing on the copy used on the copyholder.

Referring more particularly to Fig. 10 it will 40 be seen that the arm 133 is provided with a beveled face 138 adapted to coact with a beveled face stop 139 carried by and projecting laterally from the bracket 130 to limit the return movement of the arm 133 and the parts controlled 45 thereby to normal position. It should be explained at this point that the compound shaft 129, 124 is free to receive a longitudinal movement in its bearing 130, as well as a turning movement in said bearing. A coiled expansion 50 spring 140 surrounds the forward section 129 of this compound shaft and is fixedly connected at one end to a collar 141 secured to the shaft section 129 by a set screw 142. The other end of this spring is fixedly connected to the bracket 55 130. The spring therefore has a twofold function, that of turning the shaft to normal position with the stops 138, 139 in contact and also of exerting a force longitudinally of the shaft to maintain the hub of the arm 133 in contact with 60 one side of the bracket 130. The effect of this is to maintain the shaft sections in the relation shown in Fig. 9 with the pins 126 seated in the slots 123 near the rear ends thereof. Should the operator desire to release the drum from control 65 of the intermittently operated actuating means which cooperate therewith, it is merely necessary to effect a downward movement of the finger piece 132 from the position shown in Fig. 1 where the arm 133 is arrested by a stop 133^a. 70 The effect of this movement is to cause the compound shaft 129, 127 to be moved forward against the expansion force of the spring 140 due to the action of the cam faces 138, 139 which tend to bring about this longitudinal displacement of the 75

compound shaft when force is exerted on the finger piece in the direction referred to. This turning movement of the shaft from normal position in a direction opposite to that which it takes during the intermittent feed operation is effective to move the link 106 in the direction of the arrow in Fig. 8 and effect a release of the pawls 102, 103 from engagement with the ratchet wheel 94 as shown in said figure, thus freeing the drum from control of its feed mechanism. The weight of the copy-carrying member 30 and the parts connected therewith together with the force of the spring 50 is then effective to cause the member 30 to be lowered, to turn the drum 86 and to wind the flexible driving connection 85 on the drum.

Referring more particularly to Figs. 1, 2 and 4, it will be seen that I have provided a rear sheet metal cover plate 143 at the rear of the copyholder, said plate being detachably secured in place by screws 144 which engage in threaded openings in rearwardly projecting posts 145 on the portions 16^a of the supporting plate 16. The sides of the cover plate 143 are bent forward (see Fig. 4) to meet the members 16^a and the working parts are thus fully housed when they are in the contracted position.

The copyholder is comparatively simple in construction, is easily manipulated, is highly effective in use, may be quickly conditioned for storing and is substantially noiseless in its operation.

Various changes may be made in the construction, and parts thereof may be employed without departing from my invention as it is defined in the accompanying claims.

What I claim as new and desire to secure by Letters Patent is:

1. A copyholder comprising a fixed supporting portion, a copyholding member mounted for up and down movement, a lazy tongs connected at one end to said supporting portion and connected at the other end to said copyholding member, and telescoping guide members one of which is connected to said copyholding member and another of which is connected to said fixed supporting portion.

2. In a copyholder, the combination of a copyholding member, a handle, a rock shaft controlled thereby, means for normally limiting the rocking movement of said shaft in its return to normal position, and means for rendering said limiting means ineffective to limit the rocking movement of said shaft in its return to normal position and thus enable the shaft to be turned beyond such normal position.

3. In a copyholder, the combination of a copyholding member, a handle, a rock shaft controlled thereby, means for normally limiting the rocking movement of said shaft in one direction, means for rendering said limiting means ineffective to limit the rocking movement of said shaft, controlling means operable by a rocking of said shaft away from said limiting means in one direction for elevating said copyholding member, and means for freeing said member from control of said controlling means by a rocking of said shaft in the opposite direction past its normal position of arrest by said limiting means, whereby the copy-carrying member is enabled to return to normal position.

4. In a copyholder, the combination of a copyholding member, and means for controlling the movements of said member comprising a rock shaft mounted for rocking and for longitudinal movement, and limiting means for normally ar-

resting the rocking movement of the shaft and for effecting a longitudinal movement thereof to clear said arresting means when unusual force is exerted against said arresting means.

5. In a copyholder the combination of a copyholding member, and means for controlling the movements of said member comprising a rock shaft mounted for rocking and for longitudinal movement, and limiting means for normally arresting the rocking movement of the shaft and for effecting a longitudinal movement thereof to clear said arresting means when unusual force is exerted against said arresting means, said limiting means comprising an arm on said rock shaft, a fixed stop with which said arm coacts, and a cam intermediate said cam and stop.

6. In a copyholder, the combination of a plurality of relatively movable members including a copyholding member movable from a contracted position to an expanded position, and means for controlling the said movement of said copyholding member comprising a drum, and a flexible controlling member wound on said drum and connected to said copyholding member and exerting a thrust against it.

7. In a copyholder, the combination of a plurality of relatively movable members including a copyholding member movable from a contracted position to an expanded position, and means for controlling the said movement of said copyholding member comprising a drum, a flexible controlling member wound on said drum and connected to said copyholding member and exerting a thrust against it, and means for intermittently actuating said drum.

8. In a copyholder, the combination of a plurality of relatively movable members including a copyholding member movable from a contracted position to an expanded position, and means for controlling the said movement of said copyholding member comprising a drum, a flexible controlling member wound on said drum and connected to said copyholding member and exerting a thrust against it, and manually controlled pawl and ratchet mechanism for intermittently actuating said drum.

9. In a copyholder, the combination of a plurality of relatively movable members including a copyholding member movable from a contracted position to an expanded position, and means for controlling the said movement of said copyholding member comprising a drum, a flexible controlling member wound on said drum and connected to said copyholding member and exerting a thrust against it, and manually controlled pawl and ratchet mechanism for intermittently actuating said drum, said pawl and ratchet mechanism including means for rendering it noiseless in its operation.

10. In a copyholder, the combination of a plurality of relatively movable members including a copyholding member movable from a contracted position to an expanded position, and means for controlling the said movement of said copyholding member comprising a drum, and a flexible controlling member wound on said drum and connected to said copyholding member and exerting a thrust against it, the construction and arrangement of the parts being such that the portion of the flexible controlling member off the drum extends thereto in a straight line that intersects the plane of the drum.

11. In a copyholder, the combination of a plurality of relatively movable members including

5 a copyholding member movable from a contracted position to an expanded position, and means for controlling the said movement of said copyholding member comprising a drum, a flexible controlling member wound on said drum and connected to said copyholding member and exerting a thrust against it, means for intermittently actuating said drum, and means operable at will to free the drum from control of 10 said means for intermittently actuating the drum in order to enable said drum to receive a reverse rotation and the copyholding member to return to a contracted position.

12. In a copyholder, the combination of a plurality of relatively movable members including a copyholding member movable from a contracted position to an expanded position, and means for controlling the said movement of said copyholding member comprising a drum, a flexible controlling member wound on said drum and connected to said copyholding member and exerting a thrust against it, means for intermittently actuating said drum, and adjustable means for varying the extent of movement of 25 the drum effected at each operation of said means for intermittently actuating the drum, thereby determining the extent of line feed of the copy sheet.

13. In a copyholder, the combination of a plurality of relatively movable members including a copyholding member movable from a contracted position to an expanded position, and means for controlling the said movement of said copyholding member comprising a drum, a flexible controlling member wound on said drum and connected to said copyholding member and exerting a thrust against it, controlling means including a finger piece operable in one direction from its normal position for intermittently 40 actuating said drum to raise said copyholding member, and means controlled by the movement of said finger piece in the opposite direction from its normal position for releasing said drum from control of its controlling means, thereby 45 enabling the copyholding member to return to contracted position.

14. In a copyholder, the combination of a plurality of relatively movable members including a copyholding member movable from a contracted position to an expanded position, and means for controlling the said movement of said copyholding member comprising a drum, a flexible controlling member wound on said drum and connected to and exerting a thrust on said copyholding member, and guiding means cooperative with said flexible controlling member to guide it in its movement to and from said drum.

15. In a copyholder, the combination of a plurality of relatively movable members including a copyholding member movable from a contracted position to an expanded position, and means for controlling the said movement of said copyholding member comprising a drum, a flexible controlling member wound on said drum and connected to said copyholding member and exerting a thrust thereon, guiding means cooperative with said flexible controlling member to guide it in its movement to and from said drum, and means for holding said flexible controlling member properly seated on said drum.

70 16. In a copyholder, the combination of a copyholding member, and means for controlling the movements thereof comprising a flexible controlling member connected to and capable of pushing on said copyholding member to elevate

it, a drum on which said controlling member is wound, and guiding means cooperative with said flexible controlling member and arranged to guide it tangentially to the drum and in a line which intersects the plane of the drum in the movement of said flexible member to and from the drum. 5

17. In a copyholder, the combination of a plurality of relatively movable members including a copyholding member movable from a contracted position to an expanded position, and means for controlling the said movement of said copyholding member comprising a drum, a flexible controlling member wound on said drum and connected to and exerting a thrust on said copyholding member, means for intermittently actuating said drum including an intermittently actuated pawl for feeding said drum, a holding pawl for holding the drum against backward turning movement, and means operable at will 20 for freeing said pawls to enable the drum to turn backwards.

18. In a copyholder, the combination of a copyholding member, and means for controlling the movements thereof comprising a drum, and means for controlling the movements of said drum including an intermittently actuated feeding member for feeding the drum, a wheel with which said feeding member coacts, a holding member cooperative with said wheel for holding the drum against backward movement, a handle, means controlled by a movement thereof in one direction from its normal position for actuating said feeding member to turn the drum forward, and means controlled by a movement of the handle in the opposite direction from its normal position for freeing said feeding and holding members from said wheel thereby enabling said copyholding member to return to normal position. 40

19. In a copyholder, the combination of a copyholding member, and means for controlling the movements thereof comprising a drum, and means for controlling the movements of said drum including an intermittently actuated feeding member for feeding the drum, a wheel with which said feeding member coacts, a holding member cooperative with said wheel for holding the drum against backward movement, a handle, means controlled by a movement thereof in one direction from its normal position for actuating said feeding member to turn the drum forward, means controlled by a movement of the handle in the opposite direction from its normal position for freeing said feeding and holding members from said wheel thereby, enabling said copyholding member to return to normal position, and adjustable means for limiting the movement of the handle in one direction from normal position, thereby varying the extent of line spacing movement effected by an actuation of the handle. 50 55

20. In a copyholder, the combination of a copyholding member, means for intermittently elevating said member, means for affording a return of said copyholding member to the first line indicating position, and independent means operable at will to enable the copyholding member to be lowered beyond the first line indicating position to a position of non-use, the construction and arrangement of the parts being such that they will be automatically conditioned during the elevation of the copyholding member beyond the first line indicating position to bring about an arrest of said copyholding member at 70 75

the first line indicating position in the next return movement thereof.

21. In a copyholder, the combination of a plurality of relatively movable members including a copyholding member movable from a contracted position to an expanded position, and means for controlling the said movement of said copyholding member comprising a drum, a flexible controlling member wound on said drum and connected to and exerting a thrust on said copyholding member, and telescopic guide members cooperating with said copyholding member to guide it in its movement.

22. In a copyholder, the combination of a plurality of relatively movable members including a copyholding member movable from a contracted position to an expanded position, and means for controlling the said movement of said copyholding member comprising a drum, a flexible controlling member wound on said drum and connected to and exerting a thrust on said copyholding member, and telescopic guide members cooperating with said copyholding member to guide it in its movement, said telescopic members operating in the nature of a dash pot to reduce the speed of the returning parts and reduce or eliminate the noise that ordinarily would be incident to the parts being arrested in the normal position.

23. In a copyholder, the combination of a line indicating member and a copyholding member movable relatively one to the other, and means for controlling the movement of the movable member comprising a flexible controlling member connected thereto and exerting a thrust thereon, and means for controlling the movement of said flexible controlling member.

24. In a copyholder, the combination of a line indicating member and a copyholding member movable relatively one to the other, and means for controlling the movement of the movable member comprising a flexible controlling member connected thereto and exerting a thrust thereon, a drum on which said flexible controlling member is wound, and means for intermittently actuating said drum.

25. In a copyholder, the combination of a line indicating member and a copyholding member movable relatively one to the other, and means for controlling the movement of the movable member comprising a flexible controlling member connected thereto and exerting a thrust thereon, a drum on which said flexible controlling member is wound, means for intermittently actuating said drum to effect a line spacing of the movable member, and means for freeing the drum from control of said drum actuating means to enable the movable member to return to normal position.

26. In a copyholder, the combination of a copyholding member, means for intermittently elevating said copyholding member a line-space at a time, means for releasing said copyholding member for return movement, a stop connected with said copyholding member and having a vertical movement therewith, a second stop with which said first mentioned stop coacts to arrest the copyholding member in its return movement to the first line indicating position, and means for affording a relative movement between said stops out of cooperative relation for releasing the copyholding member from its arrested first line indicating position and enabling it to drop to a position of non-use.

27. In a copyholder, the combination of a

copyholding member, means for intermittently elevating said copyholding member a line-space at a time, means for releasing said copyholding member for return movement, a stop pivoted on said copyholding member and having a vertical bodily movement therewith and also adapted to turn on its pivot into and out of effective position, and a second stop with which said first mentioned stop coacts to arrest the copyholding member in its return movement to the first line indicating position, a pivotal movement of said first mentioned stop releasing the copyholding member from its arrested first line indicating position and enabling it to drop to a position of non-use.

28. In a copyholder, the combination of a copyholding member, means for intermittently elevating said copyholding member a line-space at a time, means for releasing said copyholding member for return movement, a stop, a second stop with which said first mentioned stop coacts to arrest the copyholding member in its return movement to the first line indicating position, and means for affording a relative movement between said stops out of cooperative relation for releasing the copyholding member from its arrested first line indicating position and enabling it to drop to a position of non-use, the construction and arrangement of the parts being such that said stops will be brought automatically into cooperative relation when the copyholding member is elevated beyond its first line indicating position.

29. In a copyholder, the combination of a copyholding member, means for intermittently elevating said copyholding member a line-space at a time, means for releasing said copyholding member for return movement, and means for arresting the copyholding member in its first line indicating position on the return thereof, said last mentioned means including means that enable the copyholding member to drop below the first line indicating position to a position of non-use when desired and to automatically bring about a restoration of said arresting means to effectiveness when the copyholding member is elevated beyond its first line indicating position, whereby the parts are automatically conditioned to effect an arrest of the copyholder at the first line indicating position when said holder is again returned.

30. In a copyholder, the combination of a copyholding member, means for intermittently elevating said copyholding member a line-space at a time, means for releasing said copyholding member for return movement, and means for arresting the copyholding member in its first line indicating position on the return thereof, said last mentioned means including means that enable the copyholding member to drop below the first line indicating position to a position of non-use when desired and to automatically bring about a restoration of said arresting means to effectiveness when the copyholding member is elevated beyond its first line indicating position, whereby the parts are automatically conditioned to effect an arrest of the copyholder at the first line indicating position when said holder is again returned, said arresting means comprising coacting stops movable into and out of cooperative relation and including means that tend to return certain of said stops to and maintain it in cooperative relation.

31. A copyholder comprising a fixed supporting portion, a copyholding member mounted for

up and down movement, a lazy tongs connected at one end to said supporting portion and connected at the other end to said copyholding member, telescoping guide members one of which 5 is connected to said copyholding member and another of which is connected to said fixed supporting portion, and means separate and distinct from said lazy tongs for intermittently elevating said copyholding member and controlling its 10 return movement to normal position.

32. In a copyholder, the combination of a copyholding member, means for intermittently elevating said copyholding member a line-space at a time, means for releasing said copyholding 15 member for return movement, and means for arresting the copyholding member in its first line indicating position on the return thereof, said last mentioned means including means that enable the copyholding member to drop below 20 the first line indicating position to a position of non-use when desired and to automatically bring about a restoration of said arresting means to effectiveness when the copyholding member is again elevated beyond its first line indicating 25 position, whereby the parts are automatically conditioned to effect an arrest of the copyholder at the first line indicating position when said holder is again returned, said arresting means comprising coacting stops movable into and out 30 of cooperative relation, the construction being such that certain of said stops are by the force of gravity automatically returned to effective position.

33. A copy holder comprising a base, an extensible frame mounted on the base, a roll of sheet material positioned transversely of the frame adjacent one end thereof and having its outer end attached to the opposite end of said frame, a coil of steel tape mounted on the base and 40 having its outer end secured to said frame, means for progressively feeding the tape upwardly to extend said frame and unroll said sheet material, means for precluding buckling of the extended tape, means for clamping copy pages at 45 the top of said frame, the pages being adapted to lie against the unrolled portion of said sheet material, an eye guide to cooperate with the copy pages, and means for returning the extended frame, tape, and sheet material to their 50 initial unextended positions.

34. A copy holder comprising a base, an extensible frame mounted on said base, said frame comprising a pair of standards consisting each of a plurality of telescopically associated tube 55 sections, one of the tube sections of each standard being fixed to said base, a top piece extending transversely between said standards and fixed at each side to the farthest extendable of the movable tube sections, a roll of sheet material positioned transversely of said frame and having its outer end attached to said top piece, means for progressively extending upwardly 60 said tube sections for raising said top piece and unrolling the sheet material attached thereto, means for clamping copy pages to said top 65 piece, an eye guide associated with immovable portions of said frame and adapted to cooperate with the copy pages, and means for returning the extended frame and sheet material to their 70 initial unextended positions.

35. A copy holder comprising a base, an extensible frame mounted on said base, said frame comprising a pair of standards consisting each of a plurality of telescopically associated tube 75 sections, one of the tube sections of each stand-

ard being fixed to said base, a top piece extending transversely between said standards and fixed at each side to the farthest extendable of the movable tube sections, means for clipping copy pages to said top piece for holding the 5 pages in depending position relative to said frame, an eye guide associated with the immovable parts of the frame and adapted to cooperate with the positioned copy pages, means for progressively extending upwardly the movable 10 tube sections to raise said top piece and carry the copy pages past said eye guide, and means for returning the frame to its unextended position.

36. A copy holder comprising a stationary 15 lower part and an extensible upper part, the latter being adapted to be collapsed to an inoperative position wherein said part extends only to a height similar to that of the lower part, means on said upper part for holding copy 20 pages, means for raising the upper part relative to the lower part, a laterally extending portion at each side of said upper part adjacent the top thereof, an eye guide pivotally mounted on said lower part and adapted to cooperate with 25 copy pages held by said upper part, the eye guide in operative position being adapted to project upwardly and having associated therewith a pair of stop members adapted when said guide is in operative position to extend into the 30 path of said laterally projecting portions of the extensible part for limiting collapsing movement of said part at an initial operative position above that of the completely collapsed 35 position thereof.

37. In a copyholder the combination, with a support, of a copyholding member vertically extensible with respect thereto, a flexible member also extensible from said support, operatively associated with said copyholding member, and 40 means for extending said flexible member with respect to said support, whereby the movement of said flexible member will be transmitted to said copyholding member.

38. In a copyholder the combination, with a 45 support, of a copyholding member vertically extensible with respect thereto, a flexible member also extensible from said support, operatively associated with said copyholding member, and means for extending said flexible member step 50 by step with respect to said support, whereby the movement of said flexible member will be transmitted to said copyholding member.

39. In a copyholder the combination, with a support, of a copyholding member vertically extensible with respect thereto, a flexible member also extensible from said support, operatively associated with said copyholding member, and adjustable means for extending said flexible 55 member step by step with respect to said support, whereby the movement of said flexible member will be transmitted to said copyholding member.

40. In a copyholder the combination, with a support and a copyholding member vertically extensible with respect thereto, of a flexible member also extensible from said support, causing upward movement of said copyholding member.

41. In a copyholder the combination, with a support and a copyholding member vertically extensible with respect thereto, of a flexible member also extensible from said support, causing upward movement of said copyholding 75

member, said flexible member consisting of spring metal having a curved section.

42. In a copyholder the combination, with a support and a copyholding member vertically extensible with respect thereto, of a flexible member also extensible from said support, causing upward movement of said copyholding member, and a line indicator mounted on, and vertically adjustable with respect to said support.

43. In a copyholder the combination, with a support, of a copyholding member vertically extensible with respect thereto, a flexible member also extensible from said support, operatively associated with said copyholding member, and unidirectionally operative means for extending said flexible member step by step with respect to said support, whereby the movement of said flexible member will be transmitted to said copyholding member.

44. In a copyholder the combination, with a support, of a copyholding member vertically ex-

tensible with respect thereto, a flexible member also extensible from said support, operatively associated with said copyholding member, and adjustable unidirectionally operative means for extending said flexible member step by step with respect to said support, whereby the movement of said flexible member will be transmitted to said copyholding member.

45. In a copyholder the combination, with a support, of a copyholding member vertically extensible with respect thereto, a flexible member also extensible from said support, operatively associated with said copyholding member, and unidirectionally operative means comprising an actuating and an actuated member for extending said flexible member with respect to said support, whereby the movement of said flexible member will be transmitted to said copyholding member, said actuating member being releasable so as to permit return movement of said actuated member.

JOSEPH PHELPS.
